UNITED STATES PATENT OFFICE.

ROY L. DANKS AND MAX L. BAKER, OF NEW HAVEN, CONNECTICUT, ASSIGNORS TO THE REGAL SILVER MFG. CO., OF NEW HAVEN, CONNECTICUT, A CORPORATION.

DESIGN FOR A SPOON OR SIMILAR ARTICLE.

Application filed February 2, 1927. Serial No. 20,589. Term of patent 14 years.

To all whom it may concern:

Be it known that we, ROY L. DANKS and MAX L. BAKER, citizens of the United States, residing at New Haven, in the county of New Haven and State of Connecticut, have invented a new, original, and ornamental Design for a Spoon or Similar Article, of which the following is a specification, reference being had to the accompanying drawing, forming part thereof.

Fig. 1 is a face view of a spoon showing our new design;

Fig. 2 is a sectional view on the line 2--2 of Fig. 1;

Fig. 3 is a rear view.

We claim:

The ornamental design for a spoon or similar article as shown.

ROY L. DANKS.
MAX L. BAKER.
